UNITED STATES PATENT OFFICE.

WALTER J. WILSON, OF SEWICKLEY, PENNSYLVANIA.

MINING AND LOADING MACHINE.

Application filed October 9, 1917. Serial No. 185,560.

To all whom it may concern:

Be it known that I, WALTER J. WILSON, a citizen of the United States, residing at Sewickley, in the county of Allegheny and State of Pennsylvania, have invented certain new and useful Improvements in Mining and Loading Machines, of which the following is a specification.

This invention relates broadly to a mining machine, particularly intended for mining coal or the like, in which the cutting element or elements serve also to elevate and convey the cuttings or excavated material out of and away from the kerf. The present invention is adapted to be embodied in a variety of particular forms of machines, for which I intend to file applications for Letters Patent, but in the present instance, the invention is diagrammatically illustrated, and will be described as embodied in an exceedingly simple form of machine.

The objects of this invention are to provide an improved mining and loading machine which will be adapted to excavate material and load it into cars or the like; to provide a machine of this character in which the cutting elements also serve to convey the material rearwardly of the cut and in such position that it may be readily disposed of; to provide a mining machine in which the cutter chains are arranged in vertical planes, or at such angles as may be desired for cutting and carrying the excavated material away at the upper portions of the cutter bars; to provide a mining machine in which the cutter chains are arranged in other than horizontal planes and the chains driven so as to draw the material out along the top portions of the cutter bars, or chain supporting elements; to provide a mining machine in which the cutter chains are driven at a comparatively high speed and arranged to elevate and carry the material to a convenient point for disposal; and, in general, to provide such an improved form of machine as will be shown and described more fully herein-after.

In the accompanying drawings illustrating this invention:

Fig. 1 is a diagrammatical view of a simple form of machine embodying this invention;

Fig. 2 is a plan view of the same;

Fig. 3 is a sectional view of the cutting and conveying element;

Fig. 4 is a plan view of a modified form of cutting and conveying element,

Fig. 5 is a side view of the same, and,

Figs. 6 to 10 are details of a coal guide or chute which may be used in connection with some forms of my machines.

In the ordinary types of "wall" and breast machines, the cutter bars are arranged so that the chains move in horizontal planes to cut the kerfs under the coal. In these machines, the operator must shovel the slack or cuttings away from the face and into the cars. In some instances the cutter bars have also been arranged in vertical planes to cut vertical kerfs, but in such cases the chains are driven so that they move in over the top of the cutter bar and out underneath the same, thereby dragging the slack or cuttings out at the bottom of the kerf where it must also be shoveled away. In accordance with my invention the cutter chain is driven in the opposite direction from that just described, so that it will pass in along the bottom of the cutter bar or supporting means, and will then pass up and out along the top of the same so as to elevate and convey the cuttings out at the top of the kerf, and from thence to any convenient point for disposal. The cutter chain is preferably driven at a relatively high speed so that the slack or cuttings will be properly ejected and also for the purpose of increasing the cutting efficiency. As shown in the drawings, 6 indicates a base or frame of any suitable form of construction which is adapted to be held in fixed position, as by means of jacks 7, or in any other well-known manner. An auxiliary frame or carriage 8 is slidably mounted in the base 6 and carries the cutting mechanism. Any suitable means for driving the carriage 8 for feeding the cutting mechanism may be used. In the present instance I have shown racks 9 on the sides of the base 6, which are engaged by pinions 10 on a shaft 11 mounted on the carriage 8, this shaft being driven by means of a chain 12 from the motor 13 on said carriage. Any suitable clutches or reversing mechanism such as commonly used on mining machines may be used in connection with this feeding device, but as such mechanism forms no part of the invention, it is not illustrated.

The carriage 8 is provided with forwardly extending side pieces 14, to which

the cutter arm or bar 15 is rigidly secured. A shaft 16 has its bearings in the side pieces 14 and is driven by means of a chain, or other suitable device 17, from the motor 13.

5 The shaft 16 is provided with a sprocket 18 for driving the cutter chain 19, this chain being of any suitable variety and bearing cutter bits 20. The forward end of the cutter bar or arm 15 is provided with an 10 adjustable guide wheel 21 for the chain 19. The bar 15 is preferably provided with guide channels 22 for guiding the cutter chain between the supporting wheels.

A shaft 23 is mounted in the arms 14 and is provided with a sprocket 24 which engages with the chain 17 and is driven thereby. The shaft 23 has a roller 25 which drives a conveyer belt 26 which is carried over guide rollers and preferably arranged to deposit the coal in the mine car 27.

In operating this type of machine, the base will be arranged adjacent to the face of the coal, with the carriage in retracted position, ready for the initial cut. The cutter bar is preferably fed in at a comparatively slow speed, while the chain is preferably driven at a much faster speed than is the common practice at the present time. This will increase the cutting efficiency as well as insure the proper conveying and discharging of the coal or material excavated. As the carriage is fed inwardly, or toward the face of the coal, a kerf or opening will be excavated and the material will be carried out and deposited on the conveyer, which then carries it to the car, so that all of the cuttings will be deposited directly in the car without manual labor. In this connection it will be noted that the conveyer may be made of sufficient length so that it will serve as a "picking table," and rock or other objectionable matter may be separated from the coal. When the initial cut has been made, the cutter bar is drawn out and the machine moved to one side and the next cut made, the operation being similar to that of a breast machine.

In the modified forms of construction shown in Figs. 4 and 5, the cutter bars carry a plurality of cutting and conveying elements which are arranged so as to cut a sufficiently wide kerf, so as to admit the body of the machine. In this instance the bars 28 carry a plurality of cutter chains 29 arranged side by side in parallel relation. In order that the cutting and excavating devices may cut a kerf sufficiently wide to admit the body or frame of the machine, the center chain is made shorter than the others, so as to clear the driving sprocket 31, which drives the shaft 32, which shaft drives the cutter chains by means of sprockets in the usual manner. A shaft 33 is mounted in the bars 28 in advance of the shaft 32, and is provided with a series of

sprockets which engage with the outer chains, so that the shaft will be driven thereby. This shaft also carries a sprocket 35 at the center for driving the center chain 36 which, in this instance, is shorter than the side chains. A guide chute or plate 37 is arranged at the rear of the chain 36 so as to guide the slack or cuttings over the sprocket wheel 31 and into position to be taken away by the conveyer. In this instance the frame or body of the machine 38, with the parts carried thereby, are made sufficiently small in proportion to the cutting and conveying member that it may pass into the kerf or opening, and in this manner the machine may be fed continuously into the coal. With this arrangement the entire frame of the machine is moved forwardly by any suitable means, as above described. In this connection it will be observed that the cutting and conveying arrangement may be made sufficiently high so that it will cut the entire seam of coal if desired. In some instances, as in the latter type of machine, the walls of a cut or kerf will serve to guide the coal from the cutting and conveying apparatus onto the conveyor which carries the coal back to the car. In other instances it may be desirable to provide a chute or guide which will coact with the cutting mechanism to carry the coal back and discharge it on the conveyor or at such point as may be desired. I have shown such a chute or guide in Figs. 6 to 10 which is illustrated as applied to the form of machines shown in Figs. 1 and 2. This comprises a fixed portion 39 which is attached to the side pieces 14 and chain guide 22. This member may be made in any desired form but as shown, consists of a pipe or tube having a slot in the lower portion thereof to permit the passage of the chain, and the discharge of the coal onto the conveyor. A series of movable, telescoping guide members 40, 41, and 42 are arranged to coact with the fixed member 39 and the guide 22 in the manner illustrated. These movable sections are preferably provided at their outer ends with bands or stop pieces 43. Bars or strips 44 are secured to the sides of the guide 22 and support the movable sections. The guides or strips 44 are notched or stepped for the different sections, such notches or steps serving to limit the outer movement of the respective sections. Of course it will be seen that any desired number of sections may be used depending upon the length of the cutter bar and the length of the telescoping portion of the fixed section.

When this guide or chute is employed, the operator pulls the telescoping sections out until they are extended their full length. As soon as the cutter bar enters the coal, the cuttings or excavated material will be 130

carried back through the chute or guide onto the conveyor. When the outer section 42 strikes the face of the coal, it will be moved back into the next adjacent section 5 and this action will continue until all of the sections have been pressed together, which will of course limit the further forward movement of the cutter bar. By 10 means of this guide or chute, the coal will all be carried back to the point of delivery without falling off at the sides of the cutter bar. Such guide or chute may of course be modified for different forms or arrangements of this invention.

15 From the above description, it will be seen that this invention contemplates broadly the arrangement for cutting and conveying the coal in the manner indicated, and I do not wish to limit the same to any 20 specific details, except as set forth in the following claims, in which I claim:

1. A mining machine comprising a relatively fixed base, a carriage movable longitudinally of said base, a support mounted on 25 said carriage, an endless flexible carrier mounted on said support, cutter bits mounted in said carrier, means for driving said carrier so that it moves forward and then up and back over the support to excavate the 30 material and carry it backwardly, and a conveyor adapted to receive the excavated material and convey it away from the carrier.

2. Cutting mechanism for a coal mining machine comprising a support, and a plurality of cutting chains each chain being provided 35 with bits and mounted on said support in parallel planes and adjacent to each other, the arrangement being such that the cutter chains will cut an opening sufficiently large to admit the support and the excavated material 40 will be conveyed along said support.

3. Cutting and conveying mechanism for a mining machine comprising a support having longitudinal guideways, a plurality of 45 cutter chains mounted on said support in substantially parallel relation and adjacent to each other, and adapted to engage with said guideways, the arrangement being such that, when the mechanism is fed into the coal, all 50 of the coal will be excavated in a space as wide as the combined cutter chains, and will

be carried up and back along said guideways.

4. In a mining machine, the combination of a cutter frame, a plurality of endless 55 chains for said cutter frame, provided with cutting devices for cutting the coal, said chains being arranged in parallel relation and sufficiently close to each other to excavate all of the material within the path of the cutter frame, means for driving said chains, and said frame being movable to cause the cutting devices to engage with the coal and carry the coal up and back along the upper portion of said frame. 60

5. Cutting mechanism for a coal mining machine, comprising a support and a plurality of cutter chains mounted on said support sufficiently close to each other to cut all of the material within the path of the 70 support and operable in vertical planes and adapted to carry the excavated material back along said support to a discharge point.

6. In a mining machine, the combination of a cutter bar and cutter chain adapted to 75 cut all of the material within the path of the bar, and a guide whereby the excavated material may be supported as it is conveyed along the upper portion of said bar.

7. In a mining and loading machine, the 80 combination of a cutter bar, a cutter chain carried by said bar and adapted to cut a kerf for admitting said bar, and a chute arranged along the upper portion of the bar whereby the chain may carry the coal 85 through said chute.

8. In a mining and loading machine, the combination of a supporting member, a cutting and conveying chain carried by said member and a movable chute arranged along 90 the top of said supporting member.

9. In a mining and loading machine, the combination of a cutter arm, a chain carried by said arm, and a telescoping coal guide mounted along the upper part of said arm. 95

10. In a mining and loading machine, the combination of a cutter arm and chain carried thereby, a telescoping coal chute arranged along the top of said arm, and guideways for said chute.

WALTER J. WILSON.
